UNITED STATES PATENT OFFICE.

PHILIP C. JOHNSON, OF CHICAGO, ILLINOIS.

MANDOLIN ATTACHMENT FOR PIANOS.

1,415,574.

Specification of Letters Patent.

Patented May 9, 1922.

Application filed September 9, 1920. Serial No. 409,113.

To all whom it may concern:

Be it known that I, PHILIP C. JOHNSON, a citizen of the United States of America, and a resident of Chicago, county of Cook, 5 State of Illinois, have invented certain new and useful Improvements in Mandolin Attachments for Pianos, of which the following is a specification.

This invention relates to musical instruments of stringed character arranged for hammer actuation, and more particularly to pianos and the like.

The main objects of the invention are to provide a piano action or striking mechanism of improved form adapted to produce sounds resembling the notes of a ukelele or similar instrument; and to provide such an attachment adapted for fitting to pianos of usual construction to accomplish the desired effect.

An illustrative embodiment of this invention is shown in the accompanying drawings, in which—

Fig. 1 is an elevation view, with the front board removed, of that part of a piano which includes the hammers and immediately related members, the view being from the right of Fig. 2.

Fig. 2 is a much enlarged section at the line 2—2 on Fig. 1, and includes a side view of a hammer and associated mechanism, the hammer being in its retracted position.

Fig. 3 is similar to Fig. 2 except that the hammer is shown in its effective striking position, with the button or string agitator in its vibrating position beneath the hammer.

Fig. 4 is a perspective view of a fragment of the tongued button-supporting member and shows a number of buttons secured to the several tongue tips.

In the construction shown in the drawings, the instrument includes a sounding board 1, strings or wires 2 related thereto in the usual manner, hammers 3 for sounding the strings, intermediary members 4 disposed between the several strings and corresponding hammers, and a support 5 for said members 4.

The bar 5 when the attachment herein described is in use, is secured rigidly in place relative to the board 1, and in front of the strings 2 from which it is spaced slightly. Secured to the back of said bar is a strip 6 of flexible material, preferably leather, having a series of downwardly projecting

tongues constituting the members 4, to the lower tips of which are secured the metallic buttons 7 arranged to strike or vibrate directly against the strings for sounding the latter.

A strip 8 of soft shock-absorbing material, as for instance felt, is secured to the opposite side of strip 6 from the bar 5 and a hard rigid strip 9, preferably of sheet metal, is secured to the outer side of the felt strip 8. The said strips 6, 8 and 9 are secured rigidly together and against said bar 5 by means of fastenings 10, such as screws or the like, but said strips are free relative to one another at and adjacent to their lower edges. The strip 9 is straight horizontally but has a peculiar curved shape vertically, adapted to limit the forward movement of the strip 6 and so adjust the swing amplitude of the tongues 4 and buttons 7. Said strip or stop 75 9 has a convex face disposed toward the hammers 3 and strip 6.

The bass strings of the instrument do not produce desirable results through the application of this improvement, and therefore the strip 6 with its tongues 4 and buttons 7 extends over only about three quarters of the bar 5 and strings 2. The left end of the felt damper strip 8, as at 8', is somewhat wider than its main body part, so as to 85 extend down into alignment with the tongues 4 and buttons 7 at the right.

The above described device, which I commonly refer to as a ukelele attachment, may be raised out of its effective position whenever desired, as will be understood, the bar 5 being carried on the free ends of a pair of pivotally mounted arms 11 swung on pivots 12.

The operation of the device is as follows: 95 When the hammer 3, swinging on its shank 3', is advanced, for instance by key action as usual in such devices, the blow is received directly by the button stem or tongue 4 adjacent to its base or point of connection to 100 the strip 6. The force of the hammer blow throws the strips 6 and 8 backward against the stop 9 where their movement is arrested. The tongue 4 and button 7 are also thrown 105 backwardly and the latter is thereby caused to strike immediately against the string 2. The tongue 4 and button 7 being very light and the button being very resilient, the latter vibrates backward and forward striking against the string. The position for vibra- 110

tion of members 4 and 7 is well shown by Fig. 3. As a result of this action the string gives forth a note corresponding in quality very closely to that of the strings of a 5 ukulele, banjo, mandolin or the like. As will be understood, the striker 7 being very light and the stem 4 being very short, the vibration period is very brief.

Although but one specific embodiment of 10 this invention is herein shown and described, it is to be understood that numerous details of the construction shown may be altered or omitted without departing from the spirit of this invention as defined by 15 the following claims.

I claim:

1. In a stringed musical device of the character described, wherein hammers are arranged for actuation, the combination of 20 an attachment comprising a stop strip, a striker supporting strip, a damper strip interposed therebetween, the second mentioned strip having tongues projecting beyond said stop strip, and strikers secured to 25 said tongues, and arranged in position for actuation by said hammers.

2. An attachment for use with a musical instrument wherein a sounding string is ar-

ranged for actuation by a hammer, said attachment comprising a stop movable into 30 position between said string and hammer, a striker located between said stop and hammer and arranged to be struck by the hammer so as to react upon the string, and a shock absorbing member arranged between 35 said stop and striker and located in the path of movement of the hammer to arrest the advance of the hammer toward the string.

3. An attachment for use with a musical instrument wherein a sounding string is arranged for actuation by a hammer, said attachment comprising a movable support, a 40 stop rigidly secured to said support and movable into position between said string and hammer, a striker carried by a stem secured to said support and located between said stop and hammer, said stem being arranged to be struck by the hammer so as to cause said striker to react upon the string, and a damper strip secured to said support 45 and located between said stop and stem, said damper strip extending into the path of movement of the hammer.

Signed at Chicago this 3rd day of Sept., 1920.

PHILIP C. JOHNSON.
